HARRY TAYLOR, OF WEST BABYLON, NEW YORK, ASSIGNOR OF ONE-HALF TO PAUL KRAUSE, OF WEST BABYLON, NEW YORK

STIPPLING TOOL

Application filed August 28, 1930. Serial No. 478,536.

This invention relates to stippling tools and stippling devices, and particularly, to that type whereby various designs may be made by stippling upon a freshly coated surface, or coating material may be transferred to the surface to form the required designs thereupon.

In stippling tools or brushes of the type heretofore known, a number of stippling members have customarily been secured to a brush head or handle by securing each member individually in place. Screws have usually been used for this purpose. Considerable time and labor must therefore be consumed in the removal of the stippling members from the brush head, when it becomes necessary to replace said members due to wear, or when said members lose their effectiveness. Furthermore, it is difficult to replace the stippling members when the design is to be varied. In such cases, the operator must provide himself with a number of tools, each provided with stippling members formed in a design differing from the other members, and he is either compelled to discard the brush head when the stippling members are worn out, or he must go to the trouble of removing each member individually from the head and substitute another therefor.

My invention contemplates the provision of a holder wherein all of the stippling members simultaneously may be firmly secured with ease and rapidity, and may all be substantially instantaneously removed when desired.

My invention further contemplates the provision of such a holder, which may be used in connection with stippling members of different designs, so that the single holder only is all that is necessary in connection with a variety of stippling members.

My invention further contemplates the provision of a unit for holding a plurality of stippling members in assembled relation, so that the entire assembly may be manipulated in one operation, and the unit readily inserted into and removed from a suitable holder therefor.

My invention further contemplates the provision of a durable stippling member formed

into either a predetermined or haphazard design and of inexpensive construction, so that it may economically be discarded and replaced by another such member after its useful life has terminated.

55

The various objects of my invention will be clear from the description which follows, and from the drawings, in which,

Fig. 1 is a vertical section, taken on the line 1—1 of Fig. 2, and partial elevation of one form of my improved stippling tool, showing the stippling members assembled therein.

Fig. 2 is an end view of the same.

Fig. 3 is a bottom plan view thereof.

Fig. 4 is a vertical section, taken on the line 4—4 of Fig. 5, of a modified form of my improved tool.

Fig. 5 is an end elevation of the same.

Fig. 6 is a detailed section of one of the stippling members and of part of the retaining plate therefor, and

Fig. 7 is a similar view of a modified form of stippling member and of the means illustrated in Figs. 1, 2 and 3 of retaining said member in place in the holder.

75

In that practical embodiment of my invention illustrated by way of example, I employ a suitable holder into which a multiplicity of stippling members may be quickly clamped in one operation, and as quickly removed, as for purposes of replacement. Referring particularly to Figs. 1, 2 and 3, the holder includes the handle 10 to which is secured the holder proper 11 corresponding to a brush head. Said head is preferably made of suitable light and inexpensive material, such as wood or its equivalent. The holder or head 11 is provided with a pair of edge guide rails as 12 and 13 secured to the lower face thereof at the edges as by means of the screws 14 and thereby forming supports for the horizontally slidable clamping member 15.

85

The holder 11 and the slide 15 are suitably shaped to slide relatively and to cooperate with each other for the purpose of clamping the stippling members 16 therebetween. Toward this end, the holder 11 is provided with a longitudinal extending groove 17 between and parallel to the rails 12 and 13. The holder 11 is further provided with a series of

90

95

100

transverse grooves 18, which are spaced apart and are parallel to each other, and arranged perpendicularly to the groove 17. The bottom of the holder is thereby cut up by said 5 grooves, to form a pair of downwardly projecting sets of blocks as 19, spaced apart by the groove 17, the blocks of each set being spaced apart by the grooves 18 therebetween. As illustrated in Fig. 3, the blocks 19 are preferably though not necessarily of rectangular 10 outline.

The grooves 18 are of greater width than the corresponding width of the blocks 19 for the purpose soon to be set forth, but the 15 grooves 17 and 18 are preferably of a depth or height substantially equal to the thickness or height of the slide 15. That edge 20 of each of said blocks 19, which is nearer the end 21 of the holder, is provided with a curved 20 indent or recess 22, adapted to receive and engage the surface of about half of the correspondingly shaped end 23 of the stippling member 16. Fitted into the groove 17 and provided with transverse arms 29 extending 25 into the grooves 18, is the slide or clamping member 15. Said slide is suitably supported for reciprocating movement relatively to the holder 11 as by means of the bolts 24, passing through the opening 25 of the slide and 30 through the slot 26 of the holder 11. As clearly shown in Fig. 1, the head of the bolt may be counter-sunk into the lower face of the slide, and the upper end of the bolt carries the nut 27. A suitable washer may be 35 interposed between the nut and the upper face of the holder 11.

As shown in Fig. 3, the longitudinally arranged portion 28 of the slide 15 substantially fills the groove 17 when the slide and 40 holder are in their operative positions. The transversely arranged arms 29 of the slide, however, only partly fill the grooves 18, whereby the slide may be moved forwardly and backwardly, as desired. At the edge 45 30 of each of the arms 29, a curved recess 31 is made, complementary to the recess 22 of the blocks 19. When the parts are in the positions indicated in the drawings, the walls of the recesses 22 and 31 each engage and 50 clamp about half of the surface of the head 23 of the stippling member, whereby said members are properly secured in place for operation of the tool.

Should it be desired to remove the stippling 55 members from the holder, all that need be done is to loosen the nuts 27 slightly, and then to move the slide 15 toward the right, as viewed in Figs. 1 and 3. Such movement separates the complementary recesses 22 and 60 31 so that the head 23 of each of the stippling members is released about half of its surface and any particular one or all of said members at one time may be readily removed. Similarly, to replace the stippling member 16 65 69 into the holder together with other similar

members, the tool is preferably held with the bottom up, and the heads 23 of such members inserted into either of the recesses 22 or 31, but preferably, into engagement with the walls of the recess 22. The stippling members are thereby held sufficiently to allow the movement of the slide 15 toward the left to bring the walls of the recesses 31 into engagement with half the surface of each of the heads 23, whereafter the nuts 27 may be tightened to hold the parts into the positions in which they are thus manually set.

Each of the members 16 may be made of any suitable slightly yieldable material such as comparatively thin fibre, stiff paper, sheet metal, rolled bakelite, leather, or any other suitable material resistant to the action of paint solvents and to which wet paint adheres to a sufficient extent to perform the stippling operation. Rubber is objectionable in this respect, since dried paint is difficult to remove from rubber, and must be removed by means of paint solvents such as turpentine or gasoline, the paint solvent also attacks the rubber and partly dissolves it so that its effective life is very short.

It will be understood that for purposes of economy, and so that the member may be discarded and a new one quickly made "on the job," the stippling member 16 may be made of paper, fabric, rags, old rubber tire tubes, or other waste material, twisted preferably into sufficiently compact form so that the ends thereof may be suitably clamped and retained between the walls of the recesses 22 and 31. When so formed, the design, of course, will be indeterminate or haphazard. It will further be understood that while I have shown stippling members having substantially closed lower ends 32 thereon of greater diameter than the heads 23 and provided with a definite predetermined design and having substantially smooth flared walls, the operative ends may be made of any design, regular or irregular, and the walls may be twisted, crimped or molded into any convenient form. It will further be understood that the stippling members may have annular or hollow ends, if desired, or that said ends may be corrugated, crimped, embossed, or grooved by any suitable process to form any suitable process to form any suitable design as may be found convenient or desirable. Furthermore, as illustrated, the heads 23 of the stippling members, while shown aligned in substantially regular formation, may be staggered into any design or position, regular or irregular, by merely changing the relative positions of the complementary recesses 22 and 31.

As shown in Figs. 4 and 5, the holder 40 of the stippling tool is provided with depending sides 41 and 42, forming a groove or opening 43 therebetween, open at the bottom. At the lower face of each of the sides

41 and 42 is arranged a rail as 39 similar to the rail 13 and similarly secured in place by the screws 44. One otherwise open end of the groove 43, is closed by the end member 45 secured to the holder 40 as by means of the screws 46. At the other end 47 of the head 40, a locking latch as 48 is pivoted as by means of the screw 49 secured to the head 40.

Means are provided for the rapid insertion 10 and removal of an entire set of stippling members 50 as a unit into and from the holder. Toward this end, the sides 41 and 42 are grooved longitudinally as at 51 for the reception of the plate 52 and the springs 53. Said plate 52 is further provided with means 15 for permanently holding the stippling members 50 in place. As illustrated, said means comprises the tubular projections 54 pressed from the plate 52 and having openings 55 there- 20 in, into which the ends 56 of the stippling members may be inserted and held. When said members 50 are made of substantially rigid material such as metal, fibre, or the like, they may be held in place permanently to the plate 25 52, as by indenting the tubular portions 54 by means of the indents 57 which enter and bear against the inserted ends 56 of the stippling members. If desired, a continuous groove 58, (Fig. 6), may replace the single indent 30 57 or a multiplicity of such indents. The plate 52 and the members 50 thus secured thereto, form a unit which can be easily and rapidly inserted into and removed from the holder. To secure said plate 52 in place, I 35 prefer to use the series of leaf springs 53, secured to the rails 43 as by means of suitable screws 60. Said leaf springs, at their ends, engage the upper surfaces 61 of the rails 39 and at intermediate points 62, engage the 40 upper wall 63 of the recess 51 when the plate 52 is removed from the holder. The springs otherwise engage the under surface of the plate at 62.

In the assembled position shown in Figs. 45 4 and 5, the latch 48 is turned into substantially vertical position to engage the adjacent end of the plate 52 and to lock said plate against sliding longitudinally. To remove the plate 52 and the stippling members 50 secured thereto, the latch 48 is turned about its pivot 49 to release the end of the plate, whereupon said plate may be moved horizontally over the springs 53 towards the right as viewed in Fig. 4, and through the open end 55 of the groove 43. Another similar plate 52 with stippling members 50 of different design may then be inserted through the open end of the groove 43, said plate sliding upon the springs 53 until one end thereof abuts 60 against the end member 45. The latch 48 may then be turned down into its vertical position to lock the plate in place ready for the stippling operation.

In the operation of my improved tool, the handle 10 is grasped by the operator and the

ends of the stippling members brought into contact with the wall to be stippled, said wall preferably having a coat of wet coating material previously thereon. Part of the wet coat adheres to and is removed by the end 70 of the stippling member in a manner well known in the art. Said end, being more or less irregular, that is, being corrugated, grooved, embossed, or otherwise shaped to contact with the wall only along predetermined lines, removes the wet coat only at predetermined areas and exposes the underlying dried coat of paint or exposes the uncoated surface, as the case may be, along areas which give the desired stippled appearance. 80

It will be understood that my improved tool may also be used for the application of paint or other coating material to a surface in the designs determined by the shape of the ends of the stippling members. This may be 85 done by dipping said members into wet paint and then bringing the ends thus wet into contact with the surface to be stippled in a manner which is well understood.

The stippling members themselves form a 90 feature of the tool. It will be understood, as previously explained, that these members may be made in the form of rosettes and in connection with the holders shown in Figs. 1 to 3 inclusive, may be very economically 95 made for quick replacement to produce a variety of designs by merely twisting a wad of paper or the like into sufficiently compact form to be gripped between the slide 15 and the holder 11 or, if desired, to be forced 100 through the tubular members 54 of the plate 52 shown in Figs. 4 and 5. When made in advance, the stippling members are economically made of molded or stamped members, or members formed in any other suitable 105 manner to produce a great variety of designs on the ends thereof. In any case, should the stippling members become worn and need replacement for any reason, they may be rapidly disassembled from the holder therefor, 110 and different members substituted.

If desired, the tubular portions 65 of the plate 52 corresponding to the tubular portions 54, may be suitably shaped as for example, in the curved shape of the heads 66 115 of the stippling member 16. When so shaped, as illustrated in Fig. 6, the entire plate is manipulated as a unit and since it carries all of the stippling members thereon, the plate is adapted to be inserted into the holder 11. Said members 16 are thereby held in position by the engagement of the walls of the recesses 22 and 31 with the heads 65, without the necessity for separate handling. 120

As shown in Fig. 7, when a wad of paper 125 is used, the end of said wad is shaped under pressure of the walls of the co-acting recesses 22 and 31 to firmly grip the stippling member and to hold it for a sufficiently long period to perform the stippling operation. Other 130

wads made on the spot may be substituted therefor as the work progresses.

It will be seen that I have provided a simple and inexpensive holder wherein a series of stippling members may be rapidly inserted and removed; that I have further provided means for holding a series of stippling members, for handling the series as a unit for insertion into and removal from my improved holder, and that I have further provided a stippling member which can be readily made "on the job" to produce a variety of designs, or which can be preformed in advance to a definite design for the purpose without standing hard wear.

While I have shown and described certain preferred embodiments of my invention, it will be understood that various changes may be made therein, as suggested, and that I do not intend to limit myself to the embodiments illustrated as exemplifying my invention, but intend to claim my invention as broadly as may be permitted by the state of the prior art and the terms of the appended claims.

25 1. I claim:

1. In a stippling tool, the combination with a series of stippling members, of a grooved holder having a handle thereon, and a slide movable relatively to, and in the groove of, said holder, the holder and the slide having complementary recesses to engage said stippling members for holding said members removably in assembled relation to the holder.

35 2. In a hand stippling tool, a series of stippling members, a holder for said members, and means slideable into operative position in said holder for removably maintaining said members in operative assembled relation to the holder, and adapted to be moved out of operative position for releasing said members from the holder.

3. In a hand stippling tool, a series of stippling members, and means for securing said members in operative position in one operation, comprising a pair of cooperating and relatively movable elements, at least one of said elements engaging the ends of all of said stippling members.

50 4. In a stippling tool, a handled holder, and a slide cooperating with said holder for securing a plurality of stippling members in operative relation to said holder by a single movement of said slide.

55 5. In a stippling tool, a handled holder, a stippling unit including a plurality of stippling members, means slideable in said holder for engaging said members and for arranging said members in substantially parallel spaced relation and into assembled relation to the head, and means for removably maintaining said engaging means in its operative position.

60 6. In a stippling tool, a plurality of stippling members, means engaging said mem-

bers for securing said members in operative position in said tool in one operation and for releasing all of said stippling members simultaneously whereby said members may be simultaneously secured in place and said members may be simultaneously removed from said tool, and means for supporting and guiding said securing means.

7. In a stippling tool, a plurality of stippling members, each of said members being flared at its operative end and being narrower at its other end, and means for detachably securing all of said members in operative position in said tool simultaneously.

8. A stippling member for a stippling tool crushed of sheet material to provide an outer surface having haphazard projections and depressions therein, said member having its operative end of larger diameter than its other end, said operative end including a series of irregular and haphazard projections and depressions spread over the entire area of said end.

9. A stippling element for a stippling tool, comprising a plate, a series of tubular extensions on said plate and stippling members inserted into and secured to said extensions.

10. Means for manipulating a series of stippling members as a unit for insertion into and removal from a holder simultaneously, comprising a plate, a series of stippling members, and means for securing each of said members to said plate, the marginal edge portions of said plate being unobstructed for insertion into a holder.

11. A design-producing member for a stippling tool, comprising an apertured plate adapted to be removably inserted into the tool, and a series of stippling members, each permanently secured to said plate and each having an operative end, and a smaller end inserted into an aperture of and secured to said plate.

12. A stippling unit adapted to be rapidly inserted into and removed from a holder therefor, comprising a comparatively thin plate, tubular projections on said plate and a series of stippling members, each having an end inserted into one of the projections, and an indented portion pressed from the tubular portion of each of said projections and engaging said inserted end of the stippling member.

13. In a stippling tool, a holder having a central longitudinal groove therein and a pair of smaller grooves substantially co-extensive with and at the edges of the longitudinal groove, a plate having its edges removably insertable into the edge grooves, means for removably maintaining said plate in said head, and a multiplicity of stippling members secured to said plate.

14. In a stippling tool, a grooved holder, a handle on said holder, a plate adapted to be inserted into and removed from the grooves

of said holder, a multiplicity of stippling members secured to said plate, spring means in said grooves for urging said plate into its operative position, and means for maintaining said plate against accidental removal from said holder.

15. In a stippling tool, a grooved holder, a plate slideable in the grooves of said holder, a plurality of stippling members carried by said plate, means for urging said plate and the members carried thereby against the holder, and removable means for locking said plate to the holder.

16. In a stippling tool, a substantially rectangular holder having depending grooved sides, and a longitudinal space between the sides and open at the other end, a plate removably inserted into the grooves of the sides, springs secured to the lower wall of the grooves of the sides and engaging the under surface of the plate for urging the plate against the upper surfaces of said grooves, a plurality of stippling members secured to said plate and movable therewith, and a latch 25 pivoted to the holder and adapted to engage the plate for normally maintaining said plate in its operative position.

17. In a stippling tool, a holder, a handle for said holder on one face thereof, spaced 30 projections separated by grooves on the other face of said holder, a slide pivoted to and movable in said grooves between said projections, said slide and said projections having complementary recesses therein, bolts passing 35 through the slide and the holder for normally preventing separation thereof and permitting relative movement thereof and adapted to secure said holder and said slide in operative relation, and stippling members adapted 40 to be removably inserted into said recesses and clamped therein in the operative positions of said slide and holder.

18. In a stippling tool, a multiplicity of removable stippling members, each provided 45 with a head, a slotted holder, spaced projections depending from one face of said holder, each of said projections having a recess therein, the wall of the recess being shaped to engage approximately half of the surface of 50 the head of a stippling member, a slide arranged between said projections, transverse arms on said slide of less width than the distance between said projections whereby said slide is movable between said projections, 55 each of said arms having a recess therein complementary to the recess on the adjacent projection, the wall of the recess in the arm being adapted to engage the remaining surface of the head of the stippling member, a bolt 60 passing through the slide and through the slot of the holder, and a nut on said bolt for tightening the bolt to fix the slide in its adjusted position.

19. In a stippling tool, a series of stippling 65 members and means for releasing all of said

members simultaneously for removal from said tool, comprising a grooved and recessed holder, a recessed slide mounted for reciprocating movement in the grooves of said holder, the recesses of said slide and said holder being shaped and arranged to engage and clamp said stippling members in operative position between the walls of the recesses, and means for securing said slide against movement relatively to the holder.

20. In a stippling tool, a multiplicity of stippling members, and means for removably securing said members in operative position simultaneously and for releasing all of said members simultaneously, comprising a pair of relatively slideable and recessed cooperating clamping elements, and means for securing said elements together, the walls of the recesses of said elements each engaging part of the surface of one of said stippling members to clamp said members therebetween in the operative positions thereof, and for releasing said members on the separation of the walls of the recesses.
